ABSTRACT: A rotor assembly for a fluid flow machine comprising a rotor hub member provided with a plurality of angularly spaced apart rotor blades, and at least one load-distributing member which transmits predetermined torsional loads between the various rotor blades, the load-distributing member being free to move with respect to all the rotor blades but engaging the latter to distribute the load whenever any rotor blade, as a result of the application thereto of such a predetermined torsional load, moves with respect to the remaining rotor blades.

ROTOR ASSEMBLY FOR A FLUID FLOW MACHINE

This invention concerns a rotor assembly for a fluid flow machine, such, for example, as a gas turbine engine compressor.

The rotor blades of such machines are commonly provided, on opposite sides thereof and midway of their radial length, with members known as "clappers" which are engageable with the clappers of adjacent rotor blades. The purpose of these clappers is to distribute between the various rotor blades of a rotor shaft any exceptional torsional load to which a particular blade may be subjected, e.g. as a result of its being struck by a bird or some other foreign body. The provision of such clappers, however, inevitably adds to the weight of the rotor blades and therefore increases the stresses at the roots thereof, and hence makes it essential to fabricate these roots of sturdy construction.

According therefore to the present invention, there is provided a rotor assembly for a fluid flow machine comprising a rotor hub member provided with a plurality of angularly spaced apart rotor blades bonded thereon, radially outwardly opening recesses being provided in the tips thereof and at least one load-distributing member which is engageable with the blades to transmit predetermined torsional loads therebetween, the load-distributing member being mounted for limited radial movement in all of the recesses and being normally free to move with respect to all the rotor blades on the rotor hub to avoid the transfer to any of the blades of centrifugal forces from the load-distributing member.

As will be appreciated, since the or each load-distributing member of the rotor assembly of the present invention is normally free to move with respect to all the rotor blades, the said root stresses are reduced and roots of less sturdy construction may therefore be provided.

The or each load-distributing member preferably comprises an annular member which is concentric with the rotor hub member. Thus, the or each annular member is preferably a floating member which is mounted for limited radial and circumferential movement within aligned recesses in the rotor blades.

The said recesses are preferably provided at the tips of the rotor blades.

The or each annular member may be formed integrally with, or may be connected to, parts which extend throughout at least a portion of the angular distance, between adjacent rotor blades and which are closely spaced from the latter.

There may be a plurality of interconnected annular members.

The or each annular member may be formed of resin-impregnated fibrous material which has been wound in situ to form the annular member.

The rotor blades may be bonded to the rotor hub member.

The invention also comprises a gas turbine engine compressor provided with a rotor assembly as set forth above.

The invention is illustrated, merely by way of example, in the accompanying diagrammatic drawings, in which:

FIG. 1 is a view, partly in section, of a gas turbine engine whose compressor is provided with a rotor assembly according to the present invention,

FIG. 2 is a broken-away perspective view showing part of the said rotor assembly, and

FIG. 3 is a broken-away view looking in the direction of the arrow 3 of FIG. 2.

In FIG. 1 there is shown a gas turbine engine 10 which may, for example, be a vertical lift engine, i.e. an engine which is adapted to produce vertical lift forces on an aircraft independently of those generated aerodynamically by forward flight thereof. For this purpose the engine 10 may have a power to weight ratio of at least 12:1.

The engine 10 has an outer casing 11 within which there are provided in flow series, a compressor 12, combustion equipment 13 and a turbine 14, the turbine exhaust gases being directed to atmosphere through a short exhaust duct 15.

The compressor 12 is a multistage axial compressor having a first rotor stage 16, a part of which is shown in FIGS. 2 and 3.

The stage 16 comprises a rotor hub member 20 which is formed of resin-impregnated fibrous material. Thus, the fibrous material may be carboniferous material, such as polyacrylonitrile, which has been resin impregnated e.g. with an epoxy resin. The fibers in the rotor hub member 20 preferably consist of, or include, fibers extending circumferentially thereof.

10 The rotor hub member 20 is provided with a plurality of angularly spaced apart rotor blades 21 which are similarly formed of resin-impregnated fibrous material and each of which has a root portion 22 which is bonded to the rotor hub member 20. Each of the rotor blades 21 is provided with three rectangular-section recesses 23 which are disposed at the tip 24 of the rotor blade. Each of the recesses 23 is aligned with the corresponding recesses in the remaining rotor blades 21.

20 Mounted for limited radial and circumferential movement within each group of aligned recesses 23 in the rotor blades 21 is a floating annular member 25 which is concentric with the rotor hub member 20 and which extends somewhat radially outwardly of the rotor blades 21. Each of the annular members 25 is formed integrally with (or, if desired, is connected to), parts 26 which extend throughout the angular distance between adjacent rotor blades 21 (or, if desired, extend throughout a portion only of the said angular distance). The parts 26 which serve to interconnect the annular members 25, are provided with surfaces 30, 31 which are closely spaced 30 from the adjacent surfaces, 32, 33 of the tips 24 of the adjacent rotor blades 21.

30 Each of the annular members 25 is formed of the said resin-impregnated fibrous material. Thus, the recesses 23 may first be coated with a releasing agent, and the fibrous material, to 35 which a resin drip is applied, may be continuously wound into these recesses. Thus, when the resin drip has been cured, an annular block of resin-impregnated fibrous material, which constitutes the annular member 25, is formed within each of the groups of aligned recesses 23.

40 Similarly, the parts 26 may be made of resin impregnated fibrous material which is formed in situ after the surfaces 32, 33 have been coated with a releasing agent.

45 During normal operation, each of the annular members 25, and the parts 26 which are bonded thereto, "float." This is because the annular members 25 are normally free to move with respect to all the rotor blades 21, so that, although the annular members 25 rotate during normal operation, there is considerable "radial slip" between the annular members 25 and the rotor blades 21. The annular members 25 therefore 50 impart substantially no root stresses to the rotor blades 21 and the root portions 22 do not therefore need to be especially sturdy. It is this which enables the rotor blades 21 to be bonded to the rotor hub member 20 as described above.

55 When, however, any exceptional torsional load is applied to a particular rotor blade 21, e.g. by reason of this blade being struck by a bird, or by any other foreign body, the rotor blade 21 so affected will move with respect to the remaining rotor blades and as a result will engage the annular members 25 and their parts 26. This will cause the annular members 25 to be moved in such a way as to engage the remaining rotor blades 21 and thus to distribute the said exceptional torsional load.

60 Since the parts 26 connect all the annular members 25, all the annular members 25 will act together whenever any such 65 exceptional torsional loads are transmitted through any of them.

We claim:

70 1. A rotor assembly for a fluid flow machine comprising: a rotor hub member, a plurality of angularly spaced apart rotor blades bonded on said rotor hub member, said rotor blades having radially outwardly opening recesses in the tips thereof, and at least one load-distributing member engageable with said blades to transmit predetermined torsional loads therebetween, said load-distributing member being mounted for limited free radial movement in said recesses and being

normally free to move with respect to all said rotor blades on said rotor hub to avoid transfer to any of said blades of centrifugal forces from the load-distributing member.

2. A rotor assembly as claimed in claim 1 in which the load-distributing member comprises an annular member which is concentric with the rotor hub member.

3. A rotor assembly as claimed in claim 2 in which the annular member is a floating member which is mounted for limited circumferential movement within aligned recesses in the rotor blades.

4. A rotor assembly as claimed in claim 2 in which the annular member is connected to parts which extend throughout at least a portion of the angular distances between adjacent rotor blades which are closely spaced from the latter.

5. A rotor assembly as claimed in claim 2 in which there are a plurality of interconnected annular members.

6. A rotor assembly as claimed in claim 2 in which the annular member is formed of resin-impregnated fibrous material which has been wound in situ to form the annular member.
